UNITED STATES PATENT OFFICE.

CHARLES W. GLIDDEN, OF LYNN, MASSACHUSETTS.

IMPROVEMENT IN SOLE TRIMMING AND BURNISHING MACHINES.

Specification forming part of Letters Patent No. 130,212, dated August 6, 1872.

To all whom it may concern:

Be it known that I, CHARLES W. GLIDDEN, of Lynn, in the county of Essex and State of Massachusetts, have invented certain Improvements in Trimming and Burnishing the Edges of the Soles of Boots and Shoes; and I do hereby declare that the following, taken in connection with the drawing which accompanies and forms part of this specification, is a description of my invention sufficient to enable those skilled in the art to practice it.

The invention relates to the construction or organization of a machine for trimming the edges of soles of boots and shoes, and to that class of such machines in which the shoe being mounted upon a suitable jack has its edge presented to the trimming device, the shoe having a reciprocating oblong and semi-rotative movement, to bring the entire length of each side from heel to toe, and the entire peripheral or curved edges of heel and toe in succession, and by a continuous movement of the shoe, to the action of the trimming tool or tools.

In my construction I use an oblong gear-plate, the line of teeth of which has a curved form corresponding to the general form in outline of a sole, which gear-plate I drive or feed by a pinion placed above it on a shaft rotating in stationary bearings, the gear-plate being on a shaft, which is supported upon a link connected to a vertical slide, and said slide being pressed up by a weighted lever, so that the link may partake of or conform to the irregular movement of the gear-plate, and said plate shall be held up to the pinion and kept in engagement therewith by the upward pressure upon the link, the plate having in its rear face a groove near its edge and equidistant therefrom, into which a stud-pin enters, said pin and groove maintaining the proper relation between the gear-plate and the pinion, and the weighted lever rendering the movements of the plate uniform and preventing strain upon the pin and groove-walls. The gear-plate shaft extends from the center of the plate, but the shoe is jacked upon a pin (extending from an arm of said shaft) which is in line with the heel or the heel part of the shank, as the jack-pin must pass through the open or leg part of the boot or shoe, and, the shoe being thus jacked, its movement corresponds to the move-

ment of the gear-plate. To the sole-edge of the shoe thus jacked and moved are applied the trimming devices, and the guiding and guarding devices, by which the depth of cut and the uniformity of edge with relation to the upper are insured.

For carrying these devices I use a compound arm, to one member of which, swinging on a horizontal pin, I pivot a vertical pin carrying a horizontal bearing, upon which are pivoted two other members, one of which carries guides for keeping the cutters in position to trim the edge and rand, and the other of which carries the edge cutter or cutters, both of the latter arms swinging or yielding horizontally, so that guides and cutters can follow the curvatures of the face of the sole, and both swinging or yielding vertically to follow the edge curvatures of the sole or the upper adjacent thereto, and the edge-cutter and the guides and rand-cutter also having provision for being relatively set for adjusting the angle of the face of the edge to be formed.

For the arms carrying the guides and cutters, arms may be substituted carrying guiding and edge-burnishing wheels; and the invention consists primarily in the combination of the gear-plate made and mounted as described, and carrying a shaft to which is fixed the shoe-holding jack, of compound arms, carrying guiding and trimming or burnishing devices so arranged that the said devices have irregular movements conforming to the movements of the edge to be trimmed or burnished, and are automatically held to such edge to effect said trimming or burnishing.

The invention also embraces other features of construction relating to the arrangement of the guides and cutters, and of the burnishing-wheels and guides, the construction of the jack, &c.

The drawing shows a machine and mechanism embodying my invention.

A shows the machine in side elevation. B is a plan of the machine. C is a front elevation of it.

a denotes a post, upon which the various parts of the machine are supported. At the front of this post is a vertical slide, b, moving on a guide-rail, c, and having jointed to its front a link, d, to the upper end of which link is pivoted the gear-plate e. This plate is made

with the oblong sole-shaped gear f , and has in its rear side the correspondingly-shaped groove g , into which extends the stationary pin h projecting from the plate i of the post. The pivot-pin j extends from about the center of the gear f , and has at its front end an arm, k , from which the jack-pin l extends, said jack having secured upon it the shoe m , the edge of which is to be trimmed or burnished. Over the gear-plate e is a gear-pinion, n , fixed on a driving-shaft, o , rotating in stationary bearings at the top of the post, the rotation of the gear imparting the longitudinal and rotative movements to the gear-plate to cause the jack to be similarly moved in order to present the whole length of sole-edge to the action of the trimming or burnishing mechanism. The slide b is jointed by a link to the front end of a lever, p , pivoted to the post, and having its rear end weighted, the stress of the weight keeping the gear-plate in position or up to the gear-pinion, so that the gear-plate and jack may be properly guided by the groove g and pin h , without tendency of the pin to bind in the groove, or of the jack to sag by its weight. The jack to which the shoe is secured is peculiar, and is shown in detail at D, E, F, and G. Said jack has two plates, q r , (which may be called heel and sole plates,) the plate q being jointed to an arm, s , extending from a tubular support, t , and the plate r from a similar arm, u , extending from the support t . Said support t is pivoted to a bearing, v , by a pin, w , and sliding in the support is a rod, x , having pins extending from it through slots in the support t , upon which pins are friction-rolls y rolling in guide-grooves z in the bearing v , said slots being eccentric to the pivotal pin w . The outer end of the slide-rod x is pivoted to the adjacent ends of the two plates q r , as seen at D and G, and when the support and slide-rod are in line with the pin l the two plates are in line, as seen at D, while when said support and rod are swung around to a right-angular position to said line the movement of the rolls y in the eccentric slots z draws in the slide-rod x and brings the plates to the relative angular position seen at G. To the front of the sole-plate r an upper stretcher, a^2 , is pivoted, said stretcher having a roll, b^2 , traveling on the arm u , and when the plates are brought into angular position this stretcher is thrown toward the plate r , as seen at G, while by straightening the plates it is thrown from the plate r , as seen at D. When the shoe is to be jacked the support and slide are swung around until the plates assume the position seen at G, and the shoe can then be easily drawn over the plates, and, when so drawn over, the support and slide are thrown back to bring the plates into the position seen at D, and the plates, in straightening, will expand or stretch against the shoe-upper and directly against the sole, so that, by the combined movement of the plates and stretcher, the shoe will be rigidly and immovably fastened upon the jack. When the slide u comes into line with the pin l

a spring-bolt, c^2 , flies into the notches d^2 and locks the slide-rod x , support t , bearing v , and plates r q in relative immovable position. The trimming or burnishing mechanism is supported upon an arm, f^2 , mounted on a horizontal bolt or pin, g^2 , extending through the end of a stationary arm, h^2 , which projects from the top of the post a . To vary and adjust the angle of presentation of the said mechanism the arm f^2 is made capable of vertical movement upon the bolt g^2 , and the sleeve by which it is mounted upon the bolt bears, at its inner end, against a lever, i^2 , also mounted on said bolt, the sleeve being tightened and held against the lever by suitable nuts upon the bolt, between one of which and the adjacent end of the sleeve is placed a suitable washer. The lever extends toward the post a , and carries at its inner end a spring-latch, k^2 , which enters a notch, l^2 , in a plate, m^2 , which plate may be made adjustable in position by means of a nut and screw, n^2 , and a slot, o^2 . The nut p^2 being loosened, the trimming or burnishing mechanism is set or adjusted to the desirable presentation thereof with reference to the sole-edge to be acted upon, (the lever-latch k^2 being in its notch,) and the nut is then tightened. This being effected, the mechanism may be raised from the shoe or from working position to apply or remove a shoe by drawing out the latch k^2 and lifting the lever i^2 , the lever i^2 and arm f^2 swinging as one. The burnishing or trimming mechanism is attached to the arm f^2 by means of a pin, q^2 , which extends down from a horizontal sleeve or bearing, r^2 , and through a vertical bearing, s^2 , at the end of the arm f^2 , the pin q^2 and its bearing r^2 , swiveling in the bearing s^2 , and being tightened by a screw and nut, t^2 . u^2 denotes the edge-trimming cutter fixed upon the arm v^2 , the shank of which arm is formed as a cylindrical pin or shaft, j^2 , journaled in the bearing r^2 , in which it may be confined and more or less tightened by a screw, x^2 . For convenience the arm may be provided with a series of cutters, u^2 , extending from a ring, y^2 , fastened upon the arm by a nut, z^2 . The cutter stands horizontally, or approximately so, and its cutting-edge extends over the edge to be trimmed from outside of the sole, and the depth of cut is gaged by a guide-foot, a^3 . This foot is, at the bottom of a shank, b^3 , connected to an arm, c^3 , which arm extends from the cutter-arm v^2 , the arm c^3 being preferably connected with the arm v^2 by means of a sleeve, d^3 , fitting upon the pin j^2 , upon which it is fastened in position by a screw, e^3 , which screw permits the arm to be adjusted in angular position with reference to the cutter-arm v^2 . The gage-foot rests upon the upper at the seam, and thereby gages the depth of cut of the edge-trimming knife from said upper, and, to trim to a more or less projecting edge, the foot is made adjustable in height, its shank b^3 passing through an arm, f^3 , extending from a pin, g^3 , which pin g^3 passes through a vertical sleeve, h^3 , at the end of the arm c^3 , and is pressed down by a spring, i^3 .

The pivot g^2 enables the guide and cutters to follow the lateral irregularities of the sole, and the pivot g^3 enables them to follow the peripheral irregularities thereof, and to keep the cutters and guide against the edge the pin g^3 is provided with two guide-rollers, k^3 , at the bottom of two projections, l^3 , from a plate, m^3 , which plate m^3 has ears n^3 , by which it is hung to pivots o^3 , extending from opposite ends of the pin g^3 . A tail-piece, p^3 , of the plate has a spring, q^3 , that bears against the bearing h^3 , and when the parts are in position to operate the gage presses upon the inner side of the sole and the rolls upon the outer side thereof, the roller-frame swiveling in conformity to the irregular or curved form of the sole-face, but keeping the gage at all times in position.

In connection with the gage and edge-cutter a rand-cutter, r^3 , may be employed, said cutter or cutter-head being fixed to or forming the bottom of the pin g^3 . The cutter-head may be formed with a shoulder that rests upon the sole-edge or upon the edge-cutter, and has a vertical lip, s^3 , on the inner face of which lip is the blade r^3 that trims the rand, the blade being presented to the face of the rand toward the upper. In the burnisher mechanism the arm c^3 has extending through it a shaft, carrying at its outer end a bevel-gear, a^4 , meshing into and driving a bevel-gear, b^4 , on a shaft, c^4 , which shaft carries another bevel-gear, d^4 , meshing into and driving a bevel-gear, e^4 , on a sleeve, f^4 , that carries a grooved pulley, g^4 , which, by a band, h^4 , is connected to a pulley, i^4 , on a shaft, k^4 , carrying a burnisher-roll, l^4 , which roll is made with a cylindrical or other shaped peripheral surface, m^4 , to run in contact with the outer edge of the sole, and two lips or flanges, n^4 o^4 , that embrace the edge and burnish the top and bottom of the sole immediately adjacent to the edge, the flange o^4 being preferably made as a ring sliding upon the shaft, and pressed up against the sole by the stress of a spring, p^4 . The shaft of the roll n^4 is journaled in a frame, q^4 , that swivels horizontally on the shaft, so that the roll and its flanges accommodate themselves to the curves as well as to the varying thickness of the sole; and to guide the roll or keep it properly presented the frame q^4 is provided with two friction-rolls, r^4 , that bear upon the outer face of the sole, (one on each side of the point of action of the roll m^4), these rolls turning on pins extending up from a slide-plate, s^4 , that slides in the frame and is pressed up to the roll by the stress of a spring, t^4 . When the frame is pressed down to hold the burnisher to the sole-edge the pressure upon the gears would tend to make them bind; to obviate which I use friction-rolls u^4 , (turning on pins extending from the frame,) which bear upward against a disk, w^4 , and, rolling against the same, enable the frame to freely swivel without affecting the gear-train.

By means of a machine having the general organization set forth, and with a trimming and burnishing mechanism substantially like

those described, the edges of the soles of boots and shoes may be rapidly, evenly, and effectively trimmed and finished.

Heretofore it has been always customary, in machine trimming or burnishing the heels of boots or shoes, to present the boot or shoe to the trimming or burnishing mechanism upon a last; but in this invention the last is entirely dispensed with so far as relates to these operations, the stretcher-plates or jack-plates holding the shoe as firmly as it could be held by a last, and its application and removal to and from the jack being effected very quickly and with the utmost ease.

In the series of cutters u^2 the cutting-edge may be made so as to form different bevels and to gage the action of the rand-cutter as the foxing of the toe of a shoe meets the cutter. I employ a device, represented at J , in which, at the side of the cutter r^3 , is a spring foot or gage, x^4 , that rides upon the upper. At each side of this foot is an auxiliary foot, y^4 z^4 , the shank of which slides in a box, a^6 , and is jointed to a connector, b^6 , said connector being pivoted at c^6 , and throwing down either foot when the other one is pressed up. Normally, the position of the two feet y^4 z^4 is just above the point of the gage-foot x^4 , but when the foot in advance strikes the foxing the other foot is pressed down, thereby raising the gage x^4 and the cutter before they reach the foxing.

I claim—

1. In combination with a boot or shoe holding jack, the slide b , link d , gear-plate e , and gear n , relatively arranged and operating substantially as shown and described.

2. In combination with the boot or shoe holding jack and mechanism to operate the same, the lever i^2 , pivoted and adjustable arm f^2 , and pivoted and adjustable sleeve s^2 , and arm c^2 , relatively arranged substantially as shown and described.

3. In combination with the arm c^3 , the adjustable cutter-arm v^2 and its cutter or cutters u^2 , substantially as shown and described.

4. The series of cutters u^2 , extending radially from the ring y^2 secured to the outer end of cutter-arm v^2 , substantially as shown and described.

5. In combination with the cutter u^2 , the gage-foot a^3 , located and operating with respect to the cutter substantially as shown and described.

6. In combination with the edge-cutter u^2 and the gage a^3 , the rand-cutter r^3 , arranged to operate substantially as shown and described.

7. In combination with the edge or rand cutter r^3 , the roller-frame m^3 and rollers k^3 , constructed and operating substantially as shown and described.

8. The arrangement of the gage a^3 , edge-cutter u^2 , and rand-cutter r^3 to yield laterally and vertically in accordance with the edge and surface curvature of the sole.

9. Also, the flanged burnisher-roll l^4 placed at the end of the shaft k^4 , which shaft is driven

from the shaft c^4 by the gears d^4 e^4 , pulleys g^4 i^4 , and band h^4 , substantially as shown and described.

10. The roll or roller flange o^4 , pressed forward by the stress of the spring p^4 , substantially as described.

11. In combination with the burnishing-roll, the guide-rolls r^4 and their frame q^4 , substantially as described.

12. In combination with the burnishing-roll, the friction-rollers w^4 and disk v^4 , arranged substantially as shown and described.

13. The jack, composed of the hinged sole and heel plates r q , operated substantially as shown and described.

14. In combination with the sole and heel

plates, the upper-stretcher a^2 , substantially as shown and described.

15. In a machine for trimming and burnishing the heel and sole edge of a boot or shoe, a jack which enters the shoe and clamps the shoe upon it, dispensing with the use of a last, substantially as shown and described.

16. In combination with the rand-cutter, the gage x^4 and the connected guide-feet y^4 z^4 , arranged and operating substantially as shown and described.

C. W. GLIDDEN.
